UNITED STATES PATENT OFFICE.

MARION R. JENKINS, OF CHILlicothe, MISSOURI.

HAY-STACKER.

1,235,804.

Specification of Letters Patent.

Patented Aug. 7, 1917.

Application filed February 1, 1916. Serial No. 75,502.

To all whom it may concern:

Be it known that I, MARION R. JENKINS, a citizen of the United States, residing at Chillicothe, in the county of Livingston and 5 State of Missouri, have invented certain new and useful Improvements in Hay-Stackers, of which the following is a specification.

The hay stacker of this invention belongs to that type of stackers which employs a 10 lifting frame having an extensible head which is adapted to be automatically extended or projected during the lifting operation, with the result that the load will be deposited on the stacker head at a point relatively 15 near the center of pivotal movement and will thereafter, during the lifting operation, be extended or lifted above the point which it would normally reach by the swinging of the frame if no additional projection were 20 afforded. This lifting or projection of the stacker head is effected by the action of cables which run over pulley blocks so disposed as to prevent the accumulation of any slack in the cables which may be objectionable 25 during the operation of the device, in that the slack cables sometimes become caught or entangled in the operating portions of the mechanism, so that the operations will be interfered with. Furthermore, 30 the arrangement of the cables and pulley blocks is one which tends to distribute the projective operation in such a manner as to prevent a sudden load being thrown on the horses or other source of power, and the 35 action furthermore is one which permits the amount of the projection to be varied to accommodate the stacker to the height of the intended stack.

The invention furthermore relates to the 40 construction of the lifting frame in such a manner as to accommodate its movements to those of the swinging hoist, whereby a maximum of strength and rigidity will be secured and the hoisting movements accommodated.

Further features will appear from the detailed description of the invention which consists in the features of construction and combinations of parts hereinafter described 45 and claimed.

In the drawings:

Figure 1 is a plan view of the stacker with the lifting frame in lowered position;

Fig. 2 is a side elevation of the same;

Fig. 3 is an enlarged detail showing the 55 lifting cables and pulleys; and

Fig. 4 is a perspective view showing the lifting frame in elevated position.

The stacker, as a whole, is carried by and mounted upon a base or foundation comprising side sills 5, which are connected by forward cross sills 6, rear cross sills 7, an intermediate cross sill 8, and side braces 9. The base or foundation serves as a mounting 60 for a rectangular shaped lifting frame which comprises side rails 10, a lower cross rail 11, an upper cross rail 12, and a pair of diagonally extending intersecting brace beams 13, which cross one another at a point X, which is slightly to the rear of the center of 65 the rectangular lifting frame, and this arrangement, while securing a maximum of strength in the lifting frame, affords the necessary space for the movements of the 70 swinging hoist presently to be described.

The front and rear cross rails, and the brace beams of the lifting frame are all secured at their ends above the upper edges of the side rails 10 of the lifting frame, and the latter are spaced to lie slightly outside 80 of and in parallel relation with the side sills, so that when the lifting frame is lowered, the side rails will lie in the same horizontal plane with the side sills, and the cross rails will lie immediately above and rest 85 on the side sills, which arrangement nests the parts together into the most compact compass and simplifies the arranging of the hoisting pulleys and cables. The rear ends of the side rails of the lifting frame are 90 pivoted by means of pivot bolts 14 to the adjacent side sills of the base, at a point between the cross sills 7 and 11.

The side rails of the lifting frame contact with a pair of extension arms 15, which 95 lie outside of and in parallel spaced relation with the side rails, and the extension arms serve to carry at their outer ends the stacker head 16 which is of the usual formation and need not be described with particularity. 100 The stacker head is of greater width than the extension arms and the connection between the head and the arms is reinforced by means of diagonal side braces 18, which extend between the extension arms and the 105 outer ends of the main cross beam 19 of the stacker head.

The extension arms are slidably mounted

outside of the side rails and are each held in sliding relation thereto by means of an outer bracket 20 which is secured to a spacer block 21 at the forward end of the adjacent 5 side rail, and this bracket, which is fixed upon the lifting frame, coöperates with an inner bracket 22 which is fixed upon the extension arm and slides therewith upon the side rail, it being understood that the arrangement 10 described is the same on both sides of the structure.

The sliding bracket 22 is connected with a pulley mounting 23 which carries a riding pulley or sheave 24, which latter coöperates with a fixed pulley or sheave 25 carried by a mounting 26 secured to the adjacent side rail, the spacing of the pulleys being such as to afford space for the necessary movement of the parts during the hoisting 15 operations. It will be noted that the pulleys are arranged to lie between the extension arms and the adjacent side rails, which arrangement is one which affords an intermediate space for the travel of the 20 cables, which latter exert a pull or draw in the direction of movement of the parts, so that no torsional pulls or strains are developed, with a resulting freedom from cramping or binding and with a reduction of 25 the friction to the smallest degree.

The sheaves or pulleys on each side of the structure coöperate with lifting cables 27. As is best shown in Fig. 3, each of the lifting 30 cables is secured at its outer end to a cross pin 28, which is carried by the mounting 26 for the fixed sheave or pulley 25, and the cable is thence passed around the riding pulley or sheave 24, thence back over the pulley 25, whence it extends through an adjustable eye 29 on the side sill of the base 35 and back to an anchorage 30, which is shown as in the form of an eye at the inner or pivoted end of the side rail of the hoisting frame.

The eyes 29 on each of the side sills can be adjusted to any one of the holes 29^a, 29^b, 29^c, etc., in the side sills, in order to vary or adjust the amount of projection of the extension arms and stacker head without occasioning any slack in the hoisting cables by reason of such adjustment. This is a very distinct advantage, in that the presence of such slack is objectionable, as tending to cause entanglement of the running gear, and 45 for the further reason that an initial slack in the cable, when taken up, will throw a sudden load on the draft animals and cause a sudden jolt or jar on the stacker head, which may tend to displace the load. Thus, 50 with the eye 29 positioned in the hole 29^a, a lesser degree of projection will be occasioned as the lifting frame is elevated, and with the eyes arranged in either of the remaining holes a correspondingly less projection 55 will be secured.

The cable arrangement is such that when the parts are in lowered position with the stacker head and extension arms retracted to their extreme position, all of the hoisting cable will in all cases be completely taken up, 70 irrespective of the adjustment of the eyes 29, which is a distinct improvement over prior constructions which employ lifting cables for the purpose of extending or projecting the stacker head.

By providing a riding pulley or sheave, the extent of the projecting movement will be but a fractional part of the lifting movement, so that the power required to effect the projecting operation will be divided without 80 increasing the travel of the horses over that required for the hoisting of the lifting frame.

The hoisting of the lifting frame is effected by means of a V-shaped hoist comprising 85 a pair of upwardly converging beams 31, which are united at their upper ends and are pivoted at their lower ends by means of pivot bolts 32 to the side sills of the base at a point within the space subtended by the intersecting braces 13 of the lifting frame, which arrangement is such that the hoisting frame and the lifting frame can be moved from lowered to raised positions, and vice versa, without contact or interference with 90 one another. The hoisting frame, when the parts are in lowered position, projects upwardly and forwardly at an angle of about forty-five degrees (45°), as shown in Fig. 2, and the upper end of the V-shaped hoisting 95 frame is connected with the forward or outer end of the lifting frame by means of link rods 33, the lower ends of which are hooked through ears 34, which extend upwardly 100 from the brackets 20, which latter are provided with rollers 35 to reduce the friction incident to the movement of the extension arms through the brackets.

The hoisting frame is provided at its upper end with a pulley 36, which coöperates 110 with a pair of inner and outer pulleys 37 and 38 carried between beams 39, which extend diagonally upward from the base and are secured at their forward ends to the intermediate cross sill 8, and are supported at 115 their rear ends by means of braces 40 carried by the rear end cross sill 7. The pulleys serve to mount a hoisting cable 41, which has one end fixed to the mounting for the pulley 36, and is thence carried around the pulleys 37, 36, and 38, and a lower pulley 42, beyond which point connection is made with a hitch for horses or other suitable source of power.

In operation, with the parts in lowered position, as shown in Fig. 2, the stacker head and extension arms will be retracted, so that the load of hay will be delivered to the stacker head at a point relatively close 125 to the center of pivotal movement of the 130

lifting frame. When power is applied to the hoisting cable, the V-shaped hoisting frame will be swung back, thereby beginning to elevate the lifting frame, and this movement of the latter will exert tension on the lifting cables, so that the projection of the stacker head will begin. These movements will be continued until the lifting frame has been raised to a point slightly forward of the vertical and a load deposited, the usual spring and cable connections 43-44 being provided to draw back the lifting frame after the load has been discharged, so that the parts will easily return to lowered position by gravity when the pull on the hoisting cable is relieved.

The arrangement of the lifting pulleys for the extension arms is such that the power required for projecting the stacker head will be most advantageously applied and distributed, and the construction and arrangement of the lifting frame is such that it can move freely above and around the V-shaped hoisting frame without contact of the latter at any point. This relationing of the parts is one which permits the lifting frame to be very strongly constructed and braced, and at the same time permits the employment of the most desirable form of hoisting frame which has heretofore been developed for the purpose intended. The construction is one which is strong, durable and efficient, and at the same time enables the necessary hoisting operations to be performed with a minimum expenditure of power and a minimum development of friction.

I claim:

1. In a hay stacker, the combination of a base, a lifting frame pivotally mounted on the base, comprising side rails held in spaced relation to one another, extension arms carrying a stacker head and mounted in slidable relation with respect to the rails of the lifting frame, a pulley carried by each of the side rails, a pulley carried by each of the extension arms, a cable fixed to one of said pulleys and passing around both of said pulleys and having its end secured against withdrawal, and means for hoisting the lifting frame, substantially as described.

2. In a hay stacker, the combination of a base, a lifting frame having side rails pivoted to the base and held in spaced relation to one another, extension arms lying outside of and in parallel relation to the side rails and slidably mounted in spaced relation thereto, a pulley mounted on each of the side rails intermediate said rails and the extension arms, a pulley mounted upon each of the extension arms and lying within said space, cables for each of the extension arms, each cable having one of its ends secured to one of the pulleys and passing around both of the coöoperating pulleys and having its opposite end secured against withdrawal,

and means for hoisting the lifting frame, substantially as described.

3. In a hay stacker, the combination of a base, a lifting frame consisting of side rails pivoted to the base and held in spaced relation in respect to one another, extension arms lying outside of the side rails and slidably mounted in spaced relation thereto, a bracket on each of the side rails for slidably mounting the adjacent extension arm, a bracket 75 on each of the extension arms, adapted to slide upon the adjacent side rail, a pulley carried by each of said latter brackets, a pulley mounted upon each of the side rails, cables each having one end secured to the last mentioned pulley and passing around both of said coöoperating pulleys and having the opposite end secured against withdrawal, and hoisting mechanisms secured to the lifting frame, substantially as described. 85

4. In a hay stacker, the combination of a base comprising side sills and cross connections, a lifting frame comprising side rails pivoted at one end to the side sills, cross rails connecting the side rails of the lifting frame, and braces for the lifting frame intersecting near the center of the lifting frame and extending diagonally substantially to the ends of the lifting frame and connected thereto near the corners thereof, 90 a V-shaped hoisting frame comprising upwardly converging bars having their lower ends pivoted on each side to the side sills at a point substantially midway of the length of the lifting frame when lowered, and extending through the spaces subtended by the intersecting braces and the side rails of the lifting frame, the relation being such as to permit of unimpeded movements of the lifting frame and hoisting frame, connections between the free ends of the hoisting frame and lifting frame, and means for swinging the hoisting frame to impart movement to the lifting frame, substantially as described. 95

5. In a hay stacker, the combination of a base, a lifting frame pivoted to the base, extension arms carrying a stacker head mounted in slidable relation with respect to the lifting frame, a lifting cable mounted to exert tension on the extension arms for the purpose of projecting the same, an anchorage for the free end of said cable, and a member through which said cable runs, adapted to be adjusted to varying positions to vary the degree of projection exerted by the cable, substantially as described. 110

6. In a hay stacker, the combination of a base, a lifting frame pivoted to the base, extension arms carrying a stacker head mounted in slidable relation with respect to the lifting frame, a lifting cable mounted to exert tension on the extension arms for the purpose of projecting the same, an anchorage for the free end of said cable, and a member through which said cable runs, 115 120 125 130

adapted to be adjusted to varying positions with respect to the center of pivotal movement of the lifting frame to vary the degree of projection exerted by the cable, substantially as described.

7. In a hay stacker, the combination of a base, a lifting frame pivotally mounted on the base, a stacker head slidably mounted with respect to the lifting frame, a lifting cable mounted to exert tension on the stacker head for projecting the same, and having its free end anchored to a suitable portion of the structure, and cable adjusting means movable toward and from the pivotal mounting for the lifting frame to vary the amount of cable available for the projection of the stacker head, substantially as described.

8. In a hay stacker, the combination of a base, a lifting frame pivotally mounted on the base, a stacker head slidably mounted with respect to the lifting frame, a lifting cable mounted to exert tension on the stacker head for projecting the same, and having its free end anchored to a suitable portion of the structure, and adjustable means through which the cable is run, adapted to be adjusted to varying positions with respect to the center of the pivotal movement of the lifting frame for varying the amount of cable available for the projection of the stacker head, substantially as described.

9. In a hay stacker, the combination of a base, a lifting frame pivotally mounted on the base, comprising side rails held in spaced relation to one another, extension arms carrying a stacker head and mounted in slidable relation with respect to the rails of the lifting frame, a pulley carried by each of the side rails, a pulley carried by each of the extension arms, a cable fixed to one of said pulleys and passing around both

of said pulleys and having its end secured against withdrawal, and an adjustable member through which said cable is run, adapted to be adjusted to varying positions to vary the degree of projection afforded without occasioning slack in the cable, substantially as described.

10. In a hay stacker, the combination of a base, a lifting frame pivotally mounted on the base, comprising side rails held in spaced relation to one another, extension arms carrying a stacker head and mounted in slidable relation with respect to the rails of the lifting frame, a pulley carried by each of the side rails, a pulley carried by each of the extension arms, a cable fixed to one of said pulleys and passing around both of said pulleys and having its end secured against withdrawal, and an adjustable member through which said cable is run, adapted to be adjusted to varying positions with respect to the center of pivotal movement of the lifting frame to vary the degree of projection afforded without occasioning slack in the cable, substantially as described.

11. In a hay stacker, the combination of a base, a lifting frame pivotally mounted on the base, extension arms carrying a stacker head and mounted in slidable relation with respect to the rails of the lifting frame, pulleys carried by the lifting frame, a pulley carried by each of the extension arms, a cable for each of the extension arms, fixed to one of the coöperating pulleys and passing around both of the coöperating pulleys, and having its end secured against withdrawal, and means for hoisting the lifting frame, substantially as described.
